CLAIM

The ornamental design for a curved flight display, as shown and described.

DESCRIPTION

FIG. 1 is a top front perspective view of a four display window embodiment of a curved flight display, showing our new design;

FIG. 2 is a front elevational view thereof;

FIG. 3 is a right side elevational view thereof, the left side being a mirror image thereof;

FIG. 4 is a top plan view thereof;

FIG. 5 is a bottom plan view thereof;

FIG. 6 is a top front perspective view of a three display window embodiment of a curved flight display, showing a second embodiment of our new design;

FIG. 7 is a front elevational view thereof;

FIG. 8 is a right side elevational view thereof, the left side being a mirror image thereof;

FIG. 9 is a top plan view thereof; and,

FIG. 10 is a bottom plan view thereof.

The support structure depicted by broken line-work in FIGS. 1 and 6 has been provided for the purpose of illustrating environment that forms no part of the claimed design.

The rear structure depicted by broken lines in FIGS. 1, 3 through 6, and 8 through 10, has been shown for the purpose of illustrating portions of the curved flight display that form no part of the claimed design.
